UNITED STATES PATENT OFFICE.

LINDSLEY SCHEPMOES, OF HASBROUCK HEIGHTS, NEW JERSEY.

DECORATIVE BLOCKS.

1,268,391.

Specification of Letters Patent.

Patented June 4, 1918.

Application filed January 29, 1917. Serial No. 145,061.

To all whom it may concern:

Be it known that I, LINDSLEY SCHEPMOES, a citizen of the United States, residing at Hasbrouck Heights, in the county of Bergen 5 and State of New Jersey, have invented a new and useful Improvement in Decorative Blocks, of which the following is a specification.

This invention has reference to decorative blocks, and, particularly, to a means by 10 which innumerable designs may be produced and the blocks may be interlocked or interchanged indefinitely for the purpose of carrying out the decorative idea over surfaces 15 of indefinite dimensions.

The blocks, primarily, have been designed for decorative purposes, such as tiling, inlays, or marquetry, wall coverings, etc.; but, 20 the blocks may be utilized also as stencils, types, printing plates, toys, pasting stamps, etc.

In order that my invention may be clearly understood, I have provided drawings wherein:

25 Figure 1 is a plan of one of my blocks or units;

Fig. 2 is a plan of another of my blocks or units;

Fig. 3 is a section substantially on the line 30 3—3, Fig. 1;

Fig. 4 is a plan of a finishing block;

Fig. 5 is a plan of a section of a partially made-up design; and

Fig. 6 is a plan of a portion of a made-up 35 design differing in characteristics from that of Fig. 4.

It should be understood that the scheme of my invention, from one aspect, is carried out through the medium of two primary or 40 unit blocks, formed to have interlocking relation, and adapted to be disposed interchangeably with others of similar structure to carry out the design effects indefinitely, regardless of whether the blocks are used 45 as tiling, coverings, linings, or are used for printing, stenciling, etc. This will be understood from the following detail description. A finishing block is also used, as will be described.

50 One of the essential features of my invention is a block or other structure 1, such as shown in Fig. 1, which is in the form of an isosceles polygon, the base or longest edge or side 2 of which is provided with a 55 wedge-shaped projection or tongue 3 disposed equidistantly between the ends of said

base 2. The polygon thus produced has the right-angle 4, the acute angles 5 and 6 at opposite ends of the base 2, the intermediate angles 7 and 8 between the ends of the base 60 and at the junction of the tongue therewith, and the two angles 9 and 10 at the opposite ends of the tongue. The complementary block 11 is identical in form and dimensions with that of the block 1, excepting that, in place 65 of the wedge-shaped tongue or projection 3, a correspondingly wedge-shaped groove or recess 12 is formed within the block midway between the ends of the longest side or base, thus producing the terminal tongues 13 and 70 14 in the general form of scalene triangles, which coöperate with the opposite ends of the wedge-shaped tongue 3 and base 2 of the block 1. These two principal blocks or units are the key to the production of many 75 designs or structures possible of formulation according to my invention.

In order to enable the designs, or the building up of the designs, to be produced accurately and uniformly, the end walls or 80 edges of the tongues or projections 3 should, at the points *a*, be equidistant from the base 2 and outer side of the tongue 3, and this is also true of the groove or recess 12 of the block 11, corresponding points *a* being indicated as equidistant from the bottom of the groove 12 and the bases 15, 16, respectively, of the tongues 13, 14. These points *a* are also equidistant from three perpendiculars 85 to the bases 3 or 12, as the case may be, said perpendiculars being dropped from the vertices of angles 4, 5 and 6, respectively. The points *a* having been thus located, the sides of the tongue 3 of block 1 should be reciprocal with the corresponding sides of the 90 groove of the block 11, and said sides should be formed by a straight line intersecting the point *a*, or formed by cyma curves, intersecting and reciprocal, each side of the point *a*. By thus constructing the tongues and 95 grooves of blocks such as 1 and 11, the unique structural arrangement, such as shown at the bottom of Fig. 5, can be 100 readily brought about.

To carry out the further feature of my 105 invention, each of the blocks 1 and 11 is correspondingly lined, surfaced, ornamented, or otherwise provided with ornamental or geometrical figures or indicia, in the instance shown in Figs. 1 and 2, in the form of parallel lines, which may be disposed so as to give, to both the surface of the block and 110

the lines, values of predetermined kind, together with characteristics the elements of which may be traced throughout all the blocks in their associated or interlocked relation, or when combined, for example, as in Fig. 5. This is one of the important features of my invention and the parallel lines, for example, can be considered as one of the basic designs for the surface ornamentation 10 of my blocks.

In determining the characteristics of the superficial lining or ornamentation of the several blocks, I locate the points *b* of each block on the edges or sides 17, 18, which are of equal length, equidistant from the angle 4 and the respective angles 5 and 6.

On the respective blocks, all lines or bands or other indicia of ornamentation or other characteristics are duplicated and terminate 20 along or with respect to the respective sides or edges 17 and 18 of the blocks, equidistant from the points *b* to the angle 4 and to the angles 5 and 6, respectively. On the tongue 3, the terminals of the lines or bands, etc., at 25 the ends of said tongue are juxtaposed with reference to, and correspond with, similar lines or bands, etc., on the tongues 13, 14, and their terminals at the inclined walls of the groove 12 of the block 11, and, said lines, etc., are also duplicated equidistant each side 30 of points *a* on the ends of the tongue 3 and the inner ends of the tongues 13, 14. If, in order to add to the ornamental effects, contrasting colors are introduced between the 35 terminals of the lines or bands along the sides 17 and 18 or along the ends of the tongue 3 and groove 12, and said colors are continued in any direction or in any configuration on the surface of the blocks, the dis- 40 position of said colors at the sides of the blocks 1 and 11 will exactly correspond so that the surface ornamentation of the blocks can be made to produce innumerable artistic effects, uniform and regular in character. 45 This will be readily understood, since the corresponding colors on the respective blocks, when the latter are interlocked or juxtaposed, as shown, in Fig. 5, will be contiguous and continuous throughout the area of the blocks, 50 which are juxtaposed. This is clearly shown in Fig. 5, as well as in Fig. 6, which latter illustrates a different scheme of surface ornamentation of the respective blocks partially carried out.

55 In order to complete the design, pattern, structure, or whatever the blocks may be adapted to produce, I have provided a finishing block 19, Fig. 4, of a form corresponding to the groove or recess 12 in the block 11; 60 and such block may be lined, ornamented, or marked correspondingly, or contrastingly, with the tongues 13, 14 of block 11, as may be desired according to the effects sought.

From the foregoing description, it will be 65 seen that essential features of my invention

are the form of the units or blocks 1 and 11, enabling them to exactly and symmetrically interlock indefinitely throughout indefinite areas, and the primary scheme of surface ornamentation of the respective blocks, founded upon characteristics which bring about continuity of the basic design on the respective blocks throughout the area of the figure, regardless of the extent thereof. And it will also be understood that the basic motif of the 75 parallel lines enables the development of a variety of surface configurations and ornamentations composed of bands of contrasting colors or ornamental effects, which, when the predetermined area is completed by the 80 requisite number of interlocking blocks, will extend in continuity from block to block, or medium employed, throughout the surface of the area and produce uniformly symmetrical design figures or characteristics. 85 This is primarily secured by making all the lines or bands or ornamental characteristics of the blocks intersect or approach the sides of the latter at predetermined angles and in such widths as to be reciprocal and continuous when the blocks are juxtaposed. Fig. 6 shows how this basic motif can be indefinitely extended and varied by the use of pairs of blocks having different surface treatment or ornamentation; and, in this figure, it will be noted that the center motif consists of a plaid design wherein the lines, bands or characteristics of the respective blocks join and continue across the base lines 90 2 of the block 1 and of the tongue 3, and the 100 base lines 15, 16 and bottom of the groove 12 of the block 11.

I desire it understood that the basic motif on surface ornamentation herein described is not confined to the polygonal form of blocks, which I have described and shown in Figs. 1 and 2, but may be applied to other forms of blocks, provided the juxtaposing principle of the blocks be substantially maintained, whereby, when they are arranged contiguously, the opposite ends of the parallel lines, bands or other ornamental characteristics, or elements thereof, will join with similar characteristics on contiguous blocks, so that the effects on one will be continued on to and through the others. 110

From the foregoing description, it will be readily understood that my interlocking blocks, with or without surface ornamentation, may be employed for the various purposes set forth and that, with surface ornamentations of predetermined characteristics, indefinite ornamental designs and beautiful effects can be produced adapted for tiling, 120 flooring, wall paper, wall linings or coverings, etc., and, when desired, for printing types, stereotypes lithographing plates, stencils, and, in fact, for innumerable purposes. 125

Having thus described my invention, what 130

I claim and desire to secure by Letters Patent is:

1. As an article of manufacture, a decorative medium having two straight, uninterrupted and equal edges converging to an angle, and a third edge, connecting said two edges, having means for interlocking with another medium.
2. As an article of manufacture, a decorative medium having two straight, uninterrupted and equal edges converging to an angle, and a third edge, connecting said two edges, having a locking tongue projecting therefrom.
3. In combination, a pair of interlocking media, each of which has two uninterrupted and equal edges converging to an angle, and each of which has a third edge, connecting said two edges, provided with means whereby the said media may be interlocked when juxtaposed.
4. As an article of manufacture, a decorative medium made in the form of an isosceles polygon the equal edges of which converge to an angle, are straight and uninterrupted, and the polygonal characteristics being carried out by the provision of a tongue extending from the body of the medium on one edge thereof.
5. As an article of manufacture, a polygonal decorative figure having two uninterrupted sides of equal length converging to an angle, and another side joining said two sides from which projects centrally an angular locking tongue.
6. As an article of manufacture, a polygonal decorative medium having two uninterrupted edges of equal length converging to an angle, and another edge joining said two edges having centrally disposed means for interlocking with another medium.
7. In combination, a pair of interlocking media, each of which is in the form of a right-angle triangle, and the perpendiculars of which are straight and uninterrupted, and each of which media has means on its hypotenuse whereby the same may be interlocked when juxtaposed.
8. A decorative block in the form of a right-angle triangle the perpendiculars of which are straight and uninterrupted, said block having a tongue projecting from its hypotenuse, in combination with a block of similar size in the form of a right-angle triangle the perpendiculars of which are straight and uninterrupted, said block having a groove in its hypotenuse, said tongue and groove having characteristics whereby the two blocks may be interlocked and intimately juxtaposed.
9. A decorative block in the form of an isosceles polygon the equal sides of which converge to an angle, said block having a tongue projecting therefrom in the form of a wedge, in combination with a block of sub-

stantially similar form, having a groove in the body thereof corresponding in shape to the tongue of the first-named block, whereby the two blocks may be interlocked and intimately juxtaposed.

10. As an article of manufacture, a decorative figure in the form of an isosceles polygon having one of its surfaces provided with decorative characteristics disposed at an angle to a majority of its sides and terminating at said sides, and the polygonal characteristics being carried out by the provision of means enabling it to interlock with a block of coöoperating characteristics.

11. As an article of manufacture, a polygonal decorative medium having two uninterrupted edges of equal length converging to an angle, and another edge joining said two edges having means for interlocking with another medium, said medium having one of its surfaces provided with decorative characteristics disposed at an angle to said uninterrupted edges and terminating at said edges.

12. In combination, a plurality of blocks of substantially similar form having means whereby they may be interlocked and intimately associated to produce any predetermined structure; each of said blocks being provided with substantially similar surface ornamentation, the characteristics of which are such as to produce a continuity of the respective design lines or characteristics from one block to the other throughout the area of the structure.

13. In combination, a plurality of media; each of said media being provided with surface ornamentation, the characteristics of which are such as to produce a continuity of the respective design lines or characteristics from one media to the other throughout the area of the structure when the media are intimately juxtaposed to produce any predetermined structure, and said media having means by which they may be interlocked without disturbing their decorative continuity.

14. In combination, a plurality of figures in the form of isosceles polygons, having structural means whereby they may be intimately interlocked indefinitely, each of said figures being provided with a surface ornamentation, the characteristics of which are such as to produce from figure to figure throughout any structure or area made thereof, a continuity of the respective design lines or characteristics, whereby highly ornamental effects can be produced with regularity throughout a predetermined area of interlocking figures.

15. As an article of manufacture, a decorative medium having one of its surfaces provided with ornamental motifs, elements of which latter are arranged so as to have a different relation to different edges of the

said medium, and which elements are arranged to terminate substantially at one or more edges of said medium so that said elements may be carried over from medium to medium of a juxtaposed group of the latter and vary the ornamental composition according to the arrangement of said media, substantially as described.

16. As an article of manufacture, a decorative medium having one of its surfaces provided with a plurality of different ornamental motifs, elements of which latter are arranged so as to have a different relation to different edges of said medium, and which elements are arranged to terminate substantially at one or more edges of said medium so that said elements may be carried over from medium to medium of a juxtaposed group of the latter and vary the ornamental composition according to the arrangement of said media, substantially as described.

17. In combination, a plurality of decorative media, each of which latter has one of its surfaces provided with ornamental composition of varying characteristics, elements of which varying characteristics are arranged so as to have a different relation to different edges of said medium, whereby to produce a substantial continuity of said elements from one medium to the other, when the media are intimately associated to produce any predetermined structure, and regardless of how said media may be juxtaposed, substantially as described.

18. A set of decorative blocks each of which is of substantially similar size and is in the form of a right-angle triangle the perpendiculars of which are straight and uninterrupted, and some of which blocks are provided with a tongue projecting from

the hypotenuse and the others with a groove in the hypotenuse, said tongues and grooves having their sides disposed and shaped so that the blocks may be interlocked and intimately juxtaposed to produce any predetermined structure regardless of whether blocks having a tongue alternate with blocks having a groove, or whether all blocks have a groove, or all blocks have a tongue.

19. A set of polygonal decorative figures each of which is of substantially similar size and each of which has two uninterrupted sides of equal length converging to an angle, and each having another side joining said two sides; some of said figures having an angular locking tongue projecting centrally from said joining side, and some having an angular locking groove extending into said side; said tongues and grooves having their sides disposed and shaped so that the figures may be interlocked and intimately juxtaposed to produce any predetermined structure regardless of whether figures having a tongue alternate with figures having a groove, or whether all figures have a tongue, or all figures have a groove.

20. As an article of manufacture, a decorative figure the major form of which is a right-angle triangle the perpendiculars of which are straight and uninterrupted, said figure having a tongue projecting from the center of its hypotenuse.

21. As an article of manufacture, a decorative figure, the major portion of which is a right-angle triangle the perpendiculars of which are straight and uninterrupted, said figure having means on its hypotenuse for interlocking with another figure.

LINDSLEY SCHEPMOES.
